UNITED STATES PATENT OFFICE.

KARL HEINEMANN, OF DUSSELDORF, GERMANY, ASSIGNOR TO RHEINISCHE METALLWAAREN- UND MASCHINENFABRIK, OF DUSSELDORF- DERENDORF, GERMANY.

AUTOMATIC FIREARM.

Application filed November 15, 1928, Serial No. 319,539, and in Germany October 11, 1927.

To prevent premature opening of the breech of automatic fire arms having a toggle-joint breech, it has already been proposed to lock the toggle-joint in the stretched position by a special locking device. In this arrangement a spring-loaded inertia slide, provided in the casing of the arm, bears against the joint of the stretched toggle levers which slide, on account of its inertia moment, releases the joint on the recoil of the arm, so that the breech may open. Such a locking device requires, however, that the arm is arranged resiliently in the direction of the recoil, so that at the firing the inertia slide moves with regard to the toggle-joint. Automatic fire arms constructed in this manner are therefore not suitable for a fixed mounting in the ordinary frames and carriages.

The object of the present invention is to obviate this draw-back for which purpose the lock for the toggle-joint is, on firing, released by a control device actuated directly by the force of the driving gases. The arm may then be rigidly mounted in a frame without preventing thereby the automatic release of the toggle-joint at the proper time. Moreover, according to the invention the undesired vibrations of the toggle-joint which are due to the sudden stop on arriving in the stretched position and which may hinder the automatic engagement of the lock are absorbed or perfectly removed by blows exerted upon a portion of the toggle-joint by a beating device swinging under the influence of the inertia or under the load of a spring. The additional blow acting upon the toggle-joint after the latter has arrived its stretched position absorbs the vibrations of the toggle-joint, so that the locking of the breech before the next firing is assured by the locking device which simultaneously comes in engagement.

In the accompanying drawing a fire arm having a fixed barrel is shown by way of example. Fig. 1 is a broken away side elevation; Fig. 2 shows a plan and Fig. 3 a cross-section on the line A—B—C of Fig. 2.

The two-part toggle-joint c, c_1 is, in a well known manner, laterally shiftably journaled upon a pivot a_1 in the casing a of the arm. The front part c_1 of the toggle-joint is, by the bolt b_1 , pivotally connected to the breech which is slidably arranged in the longitudinal axis of the arm. A spring, not

shown in the drawing, presses upon a projection of the hind part c of the toggle-joint and tends to stretch the latter and to close the breech. In the closed position of the breech the toggle-joint c, c_1 is bent inwardly a little beyond its stretched dead centre position and a projection b_2 of its middle joint bears, under the pressure of the closing spring, against a stop surface of the casing a .

Upon the casing of the arm and gripping over this a locking pawl e is journaled which is actuated by a spring d and engages behind a projection c_2 of the toggle-joint part c when the breech is closed. By this means the stretched toggle-joint is prevented from bending outwardly. Upon a pivot c_3 of the toggle-joint part c a pawl lever f is swingable in a vertical plane the front end f_1 of which extends below the projection e_1 of the locking pawl e . The lower cam-like edge f_2 of the lever f lies in the path of the laterally bent end of a longitudinally movable rod g . This rod g is, in known manner, connected to a gas catching sleeve, not shown in the drawing, which is arranged in front of the barrel mouth.

On firing, the rod g is shifted forwardly by the gas catching sleeve. The bent end g_1 of the rod g then slides along the cam-like face f_2 of the pawl lever f and lifts this lever f so far, that by the latter the locking pawl e is swung until the projection c_2 of the toggle-joint is released. During the continued forward movement the end g_1 of the rod g runs against the roller c_4 and thereby the middle joint b of the toggle-joint is, in a well known manner, bent outwardly beyond the dead centre position, whereupon the further opening of the breech is effected by the recoil of the driving gases. As soon as the action of the driving gases upon the gas catching sleeve ceases, the rod g returns, under the action of a spring, to its position of rest and the locking pawl e drops into the locking position.

At the flattened front end of the bolt c_3 of the toggle-joint lever c a beating lever h is mounted swingably in the path of the toggle-joint lever c upon a pivot c_5 . A spring i resiliently holds the front end of the beating lever h in a certain distance from a handle c_6 carried by the toggle-joint lever c . If on closing of the breech the toggle-joint c, c_1 is, after passing beyond the stretched dead centre position, suddenly stopped by

meeting with the stop surface of the casing, the beating lever h swings on account of its inertia and exerts one or several powerful blows upon the handle c_6 of the toggle-joint. 5 These blows or impulses absorb the arising vibrations of the toggle-joint, prevent back-swinging of this joint beyond the dead centre position and assure the proper and due engagement of the temporarily disengaged 10 locking pawl e behind the nose c_2 of the toggle-joint.

To open the breech by hand, the locking pawl e may be disengaged by pushing a finger of the hand gripping over the handle 15 c_6 underneath the pawl. According to another construction, not shown in the drawing, means may be provided for automatically disengaging the pawl e by exerting a pull on the handle c_6 . For this purpose the handle 20 c_6 may, for instance, be resiliently and swingably connected to the toggle-joint lever c and may carry a lifting cam which when the

handle c_6 is pulled back disengages the pawl e . 25

What I claim is:

1. In an automatic fire arm, a toggle-joint breech, a locking device for locking said toggle-joint in its stretched position, a control device actuated by the driving gases for automatically disengaging the said locking device on firing and a swinging beating member bearing against the said toggle-joint in its stretched position and absorbing or removing, by inertia or by the load of a spring, 30 vibrations of said toggle-joint. 35

2. In an automatic fire arm, a toggle-joint breech and a swinging beating member bearing against the said toggle-joint in its stretched position and absorbing or removing, by inertia or by the load of a spring, 40 vibrations of said toggle-joint.

In testimony whereof I have affixed my signature.

KARL HEINEMANN.
